Herbert Bernard Moriarty
INVENTOR

UNITED STATES PATENT OFFICE.

HERBERT BERNARD MORIARTY, OF MEMPHIS, TENNESSEE.

CAP OR CROWN PULLER.

Application filed May 1, 1922, Serial No. 557,546. Renewed May 12, 1924.

To all whom it may concern:

Be it known that I, HERBERT BERNARD MORIARTY, a citizen of the United States, residing at Memphis, in the county of Shelby and State of Tennessee, have invented 5 certain new and useful Improvements in Cap or Crown Pullers, of which the following is a specification.

My said invention relates to a cap or 10 crown puller for such caps or crowns as are commonly used on bottles containing beverages. It is an object of the invention to provide a puller which can be fastened by screws to a counter or wall and under which 15 the cap end of the bottle can be hooked and the cap removed without danger of damage to the outer lip of the neck.

It has been found that the pullers as now 20 made frequently chip off the outer lip of the bottle thus making its further use with caps or crown impossible. The chips of glass also often get into the contents of the bottle which renders consumption thereof unsafe because of the possibility of swallowing 25 such chips.

By the use of my device such danger is obviated and damage to the bottle is also prevented with resulting economy.

Referring to the accompanying drawings 30 which are made a part hereof and on which similar reference characters indicate similar parts,

Figure 1 is a front elevation of my device,

Figure 2 an end elevation, and

Figure 3 a section on line A—A of Figure 1.

In the drawings reference character 1 indicates the rear portion or base of the device which is adapted to be fastened to a counter 40 or wall by means of screws passing through the openings indicated in Figure 1 or in any other convenient manner. Rigidly connected to the base and preferably integral therewith is an overhanging extension 2 having a lip 3 behind which is a recess containing a filling of rubber or composition 4 into which the cap on the bottle is indented by the pressure of the hand on the rear end of the bottle. This is intended to expose the 45 lip 3 just sufficiently to catch the edge of

the cap and pull it off without, however, exposing so much of the lip as to cause it to hook into the neck of the bottle and chip its edge.

At the lower end of the base is another 55 projection or ledge 5 which extends outward and acts as a rest for positioning the lower edge of the cap. This projection helps to force the cap into the rubber when a downward pressure is given to the free end of the 60 bottle and is intended to be spaced from the lip just sufficiently to cause the upper edge of the cap to engage the lower part of the lip.

It will be understood that my device may 65 be modified in various ways within the scope of the invention as defined in the appended claim. For example the device may take various shapes and different elements thereof may be made separable or integral and of 70 various forms either for strength or ornament. The pad 4 may also assume other forms so long as it offers a yielding resistance to the bottle top whereby it acts to hold the opposite edge of the cap down on ledge 75 5. Therefore I do not limit myself to the specific form shown in the drawings and described in the specification but only as indicated in the appended claim.

Having thus fully described my said invention, what I claim as new and desire to 80 secure by Letters Patent, is:

A puller for bottle caps or crowns comprising a base, an overhanging forward extension thereon, a lip on the extension 85 adapted to hook the cap on a bottle, said lip having a recess located directly behind the same, and a yieldable filler in the recess, the filler being adapted to prevent the metal from coming in contact with the neck of the 90 bottle being opened, substantially as set forth.

In witness whereof I have hereunto set my hand at Memphis, Tennessee, this 28th day of April, 1922.

HERBERT BERNARD MORIARTY.
